UNITED STATES PATENT OFFICE.

CHESTER I. HALL, OF FORT WAYNE, INDIANA, ASSIGNOR TO GENERAL ELECTRIC COMPANY, A CORPORATION OF NEW YORK.

THERMAL RESPONSIVE MANUALLY-OPERABLE SWITCH.

Application filed July 11, 1921. Serial No. 483,729.

To all whom it may concern:

Be it known that I, CHESTER I. HALL, a citizen of the United States, residing at Fort Wayne, in the county of Allen, State 5 of Indiana, have invented certain new and useful Improvements in Thermal Responsive Manually-Operable Switches, of which the following is a specification.

My invention relates to improvements in 10 electric switches and in particular to electric switches which are automatically operated responsively to the heating effect of an electric current.

One of the objects of the invention is to 15 provide a switch which may be manually closed, and either manually opened with a snap action, or automatically opened with a snap action in response to the heating effect of a predetermined current for a pre- 20 determined time interval.

Although not necessarily limited thereto, the invention is adapted to be used in a tumbler type of switch in which a pivoted button is provided for closing the switch 25 when thrown to one position and for opening the switch when thrown to its other position.

The invention relates to various advantageous features of construction and arrangement which will be pointed out particularly hereinafter, and the scope of the invention will be indicated in the appended 30 claims.

For a better understanding of the invention, reference is had to the accompanying drawing which shows an embodiment of the invention for purposes of illustration, and in which Fig. 1 is a plan view of an electric switch with the cover removed to show the 35 switch operating mechanism; Fig. 2 is a cross-sectional view of the switch; and Fig. 40 3 is a detail for the purpose of showing the principle of operation of the switch.

For the purpose of quickly obtaining an 45 understanding of the invention, reference is first had to Fig. 3 in which the pivotally mounted circuit controlling switch element 10 is biased to the position shown in the drawings by means of the spring 11. The 50 switch element is adapted to be depressed into circuit closing position by means of the pivotally mounted button 12 which is adapted to make engagement with the right hand end of the switch element 10. This operating 55 button 12 carries a pivotally mounted

operating rod 13 which is provided for effecting the manual opening of the switch when desired. The switch element is maintained in the circuit closed position by means of the thermostatic element 14 which 60 serves as a latch and is adapted to make abutting and sliding engagement with the arm 15 of the switch element. The thermostatic element is adapted to be heated in accordance with the current through the 65 switch by means of the heating coil 16 which is wound on and insulated from the element. The arrangement is such that when the switch is closed by the operation of the operating button, the end of the switch element 10 is brought into engagement with the resiliently mounted friction member 17, and the switch will be maintained closed by the thermostatic latch 14 until a current of a predetermined value has persisted for a pre- 70 75 determined time interval, whereupon the latch 14 will flex to the position shown in Fig. 3, and thus slide free of the arm 15 and thereby permit the switch element to return quickly with a snap action to the open position in accordance with the bias of the spring 11.

The various parts of the switch are mounted upon a supporting casing 18, which is provided with a cover 19 through which the 80 manually operative, pivoted, operating button 12 is adapted to pass so that the switch may be operated from the outside of the casing by turning the button 12 back and forth about its pivotal support. The thermostatic latch 14 is adjustable with respect to the arm 15 connected to the switch element by means of the adjusting screw 20, and the arrangement is such that by raising the thermostatic latch the time taken by the 85 latch in releasing the switch member to return to the open position for a given value of current will be increased. This adjustment may be effected either when the switch is open or when the switch is closed. 90 Turning the adjustment screw 20 in the opposite direction will shorten the time interval for opening. By reference to Fig. 1 it will be seen that the switch element 10 is adapted to make electrical contact between 95 the stationary contacts 21 and 22 when the switch is closed, and it will also be seen that when the switch is closed the heating coil 16 is included in the circuit completed through the terminals 21 and 22. 100 105 110

It will be observed that I have provided a very neat and convenient arrangement for protecting electric circuits in accordance with the heating effect of the current in the 5 circuit. It will also be seen that the switch is adapted to be manually closed by pressing the tumbler or pivoted operating button 12 to the right, and that the switch can either be manually operated to return to the open 10 position with a snap action by tilting the tumbler 12 to the left, thereby bringing the operating rod 13 into engagement with the thermal element 14 and flexing the latter to release the switch element 10, or the switch 15 may be automatically opened responsively to the heating effect of the current in the controlled circuit by the flexing of the thermostatic latch 14 resulting from the heating thereof by the heating coil 16. Because of 20 the fact that the free end of the thermostatic latch makes a sliding and abutting engagement with the switch member, the friction is very small and the switch may be very easily 25 adjusted to open at various time intervals for a given value of current. Although the switch has a comparatively few simple parts which can readily be enclosed within the casing of the ordinary tumbler switch, the 30 switch is nevertheless reliable and effective in operation.

In accordance with the provisions of the patent statutes, I have described the principle of operation of my invention, together 35 with the apparatus which I now consider to represent the best embodiment thereof, but I desire to have it understood that the apparatus shown is only illustrative and that the invention can be carried out by other means.

40 What I claim as new and desire to secure by Letters Patent of the United States, is:—

1. A thermal responsive manually operable switch comprising a pivotally mounted circuit controlling switch element, means for biasing the same to the open position, an electrically heated thermostatic latch for holding the said switch element in circuit closed position against its bias to the open 45 position, the said latch mounted with one end thereof in position to make abutting and sliding engagement with the said switch element and the said end of the latch freely movable to slide out of engagement with the 50 said switch element to release the same in accordance with the flexing of the latch due to the heating thereof, and manually operable means for mechanically moving the switch element to the closed circuit position and for flexing the said latch to release the 55 switch element to return to the open circuit position independently of the heating of said thermostatic latch.

2. A thermal responsive manually operable switch comprising a pivoted circuit controlling switch element biased to the open 65 position, a thermostatic latch for holding the said switch element in circuit closed position against its bias to the open position, an electric heating coil for heating the latch responsively to the current through the 70 switch to cause the latch to flex and thereby release the switch element, and a pivoted manually operable member for moving the switch element to the closed circuit position and for flexing the latch to release the said 75 element to return to its normal open position.

3. A thermal responsive manually operable switch comprising a pivoted circuit controlling switch element, means for biasing 80 the same to the open position, an electrically heated thermostatic latch for holding the said switch element in circuit closed position against its bias to the open position, the said latch mounted with a free end thereof in sliding abutting engagement with the said switch element and arranged to slide out of holding relation with the switch element when the latch is flexed due to the heating 85 thereof, means for varying the relative positions of the said latch and switch element for adjusting the time interval of the automatic opening of the switch for a given 90 value of current, and a pivotally mounted manually operable member for moving the 95 switch element to the closed position and for flexing the said latch to release the said element to return to the open position.

4. A thermal responsive tumbler switch comprising a casing, a pivoted circuit controlling switch element and a cooperating stationary switch element mounted within said casing, the said pivoted switch element being biased to the open position, an electrically heated bi-metallic thermostatic latch 100 having one end secured to said casing and the free end thereof disposed in sliding latching relation with said switch element for holding the same in the closed position 105 against its bias to the open position and arranged to slide out of latching relation with said switch element when the said latch is flexed due to the heating thereof, and a pivotally mounted manually operable tumbler 110 extending through said casing and arranged to move the said switch element to the closed position when operated in one direction and to mechanically flex the said latch to release 115 the said switch element to return to the open position when operated in the other direction.

In witness whereof, I have hereunto set my hand this 1 day of July, 1921.

CHESTER I. HALL.
